UNITED STATES PATENT OFFICE.

WILHELM SCHMIDT, OF CASSEL-WILHELMSHÖHE, GERMANY, ASSIGNOR TO SCHMIDT'SCHE HEISSDAMPF GESELLSCHAFT M. B. H., OF CASSEL-WILHELMSHÖHE, GERMANY, A CORPORATION OF GERMANY.

AUTOMATIC ENGINE-GOVERNOR.

1,107,204.

Specification of Letters Patent. Patented Aug. 11, 1914.

Application filed February 25, 1914. Serial No. 820,835.

To all whom it may concern:

Be it known that I, WILHELM SCHMIDT, a subject of the Emperor of Germany, and a resident of Cassel-Wilhelmshöhe, Germany, have invented certain new and useful Improvements in Automatic Engine-Governors, of which the following is a specification.

My invention relates to engine governors for reciprocating engines and is especially adapted and intended for engines of the type shown in my German Patent Number 76,651 of September 4, 1894. In the engine there disclosed the steam or driving medium is admitted by the aid of an inlet element which opens and closes automatically under the influence of pressure changes produced by the moving piston with which the inlet element is associated. The structure and operation here disclosed may be said to be a modification of and an improvement upon that disclosed in my application for United States patent for engine governors, Serial No. 666,275, filed December 16, 1911.

It is the object of my invention to provide an engine governor of the type indicated in which the loss of steam or driving fluid consequent upon the operation of the governor shall be very small.

A further object of my invention is to provide a governor of the type indicated which shall be simple and reliable.

Other objects will appear as the specification proceeds.

My invention will be better understood by referring to the drawings in which—

Figure 1 represents a longitudinal section through one end of a cylinder and piston embodying a preferred form of the invention; Figs. 2 and 3 show respectively similar sections of two modifications of my invention, the cylinder and inlet valve features being omitted.

Referring to Fig. 1 of the drawings the steam cylinder A is provided with a piston B, steam inlet C, and outlets D controlled by said piston. In the cylinder end is a ring shaped inlet opening E controlled by a main or ring valve c lying in the steam inlet chamber d. This inlet chamber is provided with a valve (relief) piston f, attached to and forming part of the ring valve c, this piston being hollow and in free permanent

communication at its bottom with the inlet chamber d. This piston f functions in a cylindrical guide way f' from the wall of which the piston is slightly separated by a space g. At top and bottom of the guide way f' there are provided upon said guide way, valve seats a and b, and rings a', b' upon the piston, are arranged to engage respectively with said valve seats when the piston is down or up, so as in either case to shut off the passage formed by the space g between the inlet chamber d and the relief chamber e. The relief chamber e has an outlet h at the top thereof going to the atmosphere or to a suitable steam collector and controlled by a pressure regulator i, which may be either operated by hand or automatically. This controlled outlet is of the same general structure as is shown and described in my application Serial Number 666,275 filed December 16, 1911, previously referred to, and my present invention is not directly concerned therewith.

The operation of my invention is as follows: Fig. 1 shows the main piston B as it appears shortly before it reaches the end of its return (upward) stroke and after the exhaust is already shut off. The ring valve c is closed thus preventing live steam from passing into the cylinder through the inlet opening E, and the ring a' is also closed against the upper valve seat a so as to prevent the passage of live steam from the inlet chamber to the relief chamber e. As soon as the exhaust is shut off, compression takes place above the main piston B and, before this compression pressure becomes as great as that of the live steam in the inlet chamber, ring valve c with valve piston f rises and permits a small quantity of steam to pass through the passage g into the relief chamber e; this passage of steam is, however, immediately cut off by the closure of ring b' against the lower valve seat b. The quantity of steam which enters the relief chamber is, therefore, quite small. The main piston now reaches the end of its stroke and begins to move forwardly (downward) at increasing velocity under the pressure of live steam which enters through the ring shaped inlet opening E, the ring valve c being now open. The pressure in the main cylinder above the piston will decrease more or less rapidly, according to the speed of the

piston, owing to the throttling in the inlet opening, and when this pressure has fallen sufficiently low, the valve piston *f* will be pressed downwardly so as to cause the ring valve *c* to close the inlet opening and the ring *a'* to set against the upper valve seat *a*. As the valve piston *f* is pushed downwardly live steam will again be admitted through passage *g* to the relief chamber. Steam from the relief chamber will pass through the outlet *h* at a speed depending upon the setting of the pressure regulator *i*.

It will be noted that my automatic governor, as above described, operates by reason of the steam which is permitted to pass through the passage *g*, relief chamber *e* and the outlet *h*. This quantity of steam is, of course, wasted so far as effective work is concerned, but by my invention the waste is made extremely small since the steam can flow through passage *g* actually only for the period during which the valve piston is in motion either up or down to seat one or the other of the rings *a* and *b* against the corresponding valve seats *a'* and *b'*. On account of this small interval of time during which the steam is actually flowing, it is possible to leave ample clearance space between relief valve and the guideway *f'* so as to insure smooth and easy working of the valve at all times.

An advantage of my invention, as herein described, is that the pressure of the ring valve *c* upon its valve seat is relieved to a considerable extent by the fact that ring *a* simultaneously seats upon the valve seat *a'*. This enables the main valve seat of the ring valve *c* to be kept narrow and obviates the disadvantages of broad seat surfaces.

40 The relief chamber *e* is not essential to the operation of my invention and the space above valve piston *f* may be entirely open to the atmosphere within the spirit of my invention.

45 The ring *b'* and valve seat *b* may be omitted within the scope of the inventive idea. The passage *g* will then be closed when the inlet opening *E* is closed and steam can only pass from the inlet chamber, through the passage *g*, while inlet opening *E* is open.

50 My invention may be embodied in various modified forms within the spirit of the same and the claims. Thus Figs. 2 and 3 show modifications especially suitable for engines where high speed of rotation is used, the moving valve system being so designed as to have very small weight and inertia. In these modifications the relief piston or the 55 main valve has a cup-like form. In Fig. 2 the valve piston moves in a cylindrical guideway *k* provided with a plurality of annular grooves whereby the contact surface between valve piston and guideway is diminished. The clearance space *l* between

valve piston and guideway *k* has preferably a radial thickness of anything between 0.02 and 0.05 mm. While the main valve *t* is open, steam passes through spaces *l* into relief chamber *n* and fills the same, and when the main valve is closed the steam contained in space *n* expands into the space *o* within the cup. As in the case of the form shown in Fig. 1, steam can only pass into the relief chamber for the very short period 75 during which the main valve is either opening or closing. The throttling due to the labyrinth of the guideway is, however, so great that practically almost no steam whatever passes during this short period. 80

In Fig. 3 the spaces between the two seat surfaces *q* and *r* fill with live steam through the clearance space *w* while the main valve *x* is open and this steam passes, when the main valve is closed, into the relief chamber *u* where it expands to the pressure of said chamber. The relief valve in this modification is guided in its movement upon the journal *v* which is provided with annular grooves having the same purpose as the 90 grooves of the piston in Fig. 2 and the length of lift is limited as before by the seat *r*.

Besides the modifications shown in Figs. 2 and 3 other forms can readily be used 95 within the inventive idea.

The essential feature of the invention resides in the interruption of the flow of driving means from the inlet chamber to relief chamber, either while the main valve is 100 closed only, or both while the valve is closed and while it is fully open.

The means by which the valves are automatically opened and closed is immaterial so far as the present invention is concerned, 105 it being merely sufficient to know that during each to and fro movement of the main piston, the valves are once opened and once closed.

Having described my invention I claim: 110

1. The combination, with an engine cylinder provided with a piston, an inlet chamber at the end of said cylinder and an inlet opening from said inlet chamber into said cylinder, of controlling means for said inlet opening comprising a main valve, means for leading steam from the inlet chamber to both sides of said main valve, and means for shutting off the steam flow through said last named means when the main valve is 115 closed.

2. The combination, with an engine cylinder provided with a piston, an inlet chamber at the end of said cylinder and an inlet opening from said inlet chamber into said cylinder, of controlling means for said inlet opening comprising a main valve, a passage for leading steam from the inlet chamber to both sides of said main valve, and an auxiliary valve for shutting off the steam 120

flow through said passage when the main valve is closed.

3. The combination, with an engine cylinder provided with a piston, an inlet chamber at the end of said cylinder and an inlet opening from said inlet chamber into said cylinder, of controlling means for said inlet opening comprising a main valve having a relief piston, a passage between the inlet

10 chamber and the outer side of the relief piston, and an auxiliary valve controlled by said relief piston for shutting off the steam flow through said passage when the main valve is closed.

15 4. The combination, with an engine cylinder provided with a piston, an inlet chamber at the end of said cylinder and an inlet opening from said inlet chamber into said cylinder, of a main valve for said inlet opening comprising a relief piston part of which lies outside the inlet chamber, a passage leading from said inlet chamber to said outlying portion of the relief valve, and means controlled by the relief valve, and 25 closing said passage when the main valve is closed.

20 5. The combination, with an engine cylinder provided with a piston, an inlet chamber at the end of said cylinder and an inlet opening from said inlet chamber into said cylinder, of a main valve for said inlet

25 opening comprising a relief piston, a relief space into which the relief piston extends which space is normally at lower pressure than the inlet chamber, a passage connecting 35 the inlet chamber and the relief space, and a valve attached to said relief piston for closing said passage when the main valve is closed.

6. The combination, with an engine cylinder provided with a piston, an inlet chamber at the end of said cylinder and an inlet opening from said inlet chamber into said cylinder, of a main valve for said inlet opening comprising a relief piston, a relief 40 space into which the relief piston extends which space is normally at lower pressure than the inlet chamber, a passage connecting 45 the inlet chamber and the relief space, a valve attached to said relief piston for closing said passage when the main valve is closed and a second valve also attached to the relief piston for closing said passage when the main valve is open.

In testimony whereof I have hereunto set 55 my hand in the presence of two subscribing witnesses.

WILHELM SCHMIDT.
